UNITED STATES PATENT OFFICE

FRITZ SINGER, OF NUERMBERG, GERMANY

EXTRUSION PRESS

Application filed August 25, 1930, Serial No. 477,567, and in Germany April 2, 1928.

This invention relates to extrusion presses, and with regard to certain more specific features, to mechanically driven extrusion presses for producing solid and hollow articles, such as bars, seamless tubes and the like.

Among the several objects of the invention may be noted the provision of means in which a container, a matrix die and a billet 10 on one hand, and a relatively movable punch and mandrel on the other hand, move toward one another.

Among other objects of the invention may be noted the provision of means for simultaneously setting into motion, but with different speeds, on the one hand a male die comprising a punch and a mandrel, and on the other hand a female die comprising a container and a matrix die; and after having performed a piercing operation and attained an extruding position of said male and female dies, to have the relative movements of said dies arrested while one of them continues its absolute movement so that it 25 may effect the proper extruding operation.

Another object of the invention is to cause the tool which effects extruding to be operated by a main driving apparatus of the press while the counter-tool is moved by means of a secondary driving means connected with and controlled by said main driving means.

Another object is to effect a quick application of a container to the punch to close the billet in the container, this being done at relatively low mechanical effect but at high speed, primarily by means of said secondary drive; then piercing with a mandrel under a higher mechanical effect through 35 said secondary drive but preventing an excessive speed drop by means of the main drive and finally causing extrusion by the punch at a high mechanical effect, the movement of the punch in this phase of the stroke being effected entirely by said main drive.

Another object of the invention is to permit the utilization of a greater part of the press stroke than has been heretofore utilized where only one tool was moved.

Another object is to effect said greater use

of the press stroke without utilizing the whole stroke.

Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated two of various possible embodiments of the invention,

Fig. 1 is a front elevation showing a press in an initial position;

Fig. 2 is a left side elevation of Fig. 1, parts being shown in section for purposes of clarity;

Fig. 3 is a vertical section taken on line 3—3 of Fig. 1, showing the press in said initial position;

Fig. 4 is a view similar to Fig. 3, but showing the position of parts subsequent to a piercing operation and prior to an extruding operation;

Fig. 5 is a view similar to Fig. 3 showing the position of the press as extrusion is completed;

Fig. 6 is a front elevation of a modified form of the invention shown in an initial position;

Fig. 7 is a cross section taken on line 7—7 of Fig. 6;

Fig. 8 is a view similar to Fig. 7, except that the press is shown in a working position after piercing and just prior to extruding; and,

Fig. 9 is a view similar to Fig. 7 showing the press after extrusion has been effected.

Similar reference characters indicate corresponding parts throughout the several views of the drawings.

Referring now more particularly to Fig. 1, there is illustrated at numeral 1, a press frame in the upper end of which is rotatably borne a crank shaft 3 formed with a center crank 5 and suitably driven from an outside source of power. The crank 5 is engaged at its crank pin by an adjustable

connecting rod 7 which in turn is coupled, by means of a ball and socket joint 9, to a slidable crosshead 11. The crosshead 11 has fastened thereto and carries a longitudinally extending mandrel 13. Because of this function of the crosshead 11, it will be referred to hereinafter as the mandrel carrier 11.

The mandrel carrier 11, in its function as a crosshead, is longitudinally slidable in a freely movably punch carrier 15, the latter being longitudinally slidable in said frame 1. The movement of the mandrel carrier 11 is limited in the punch carrier 15 by direct contact between the two at a certain phase of the forward stroke and by contact by the carrier 11 with an abutment 17 a certain phase of the back stroke. Thus the punch carrier 15 is gravitationally suspended from the mandrel carrier 11 but can be pushed upwardly some distance, because of the relative movement provided between these two members 11, 15.

At its lower end, the punch carrier 15 supports a punch 19 which, as will be seen later, serves billet enclosing and extruding purposes. This punch is interiorly provided with a hole 21 to provide a slidable bearing for the mandrel 13. The mandrel 13 and punch 19 comprise in effect a forming tool cooperating with elements to be described.

From the above it will be seen that the construction so far described comprises a frame 1 with a cooperating slider-crank mechanism 3, 5, 7, 11 and 15, said mechanism having compound sliders 11, 15. The elements 3, 5 and 7 will hereinafter be referred to as the main or primary driving means. As long as the slider 15 hangs from the slider 11 at the abutment 17, there is no relative motion between these parts. Their absolute movements with respect to frame 1 are the same.

However, I provide means herein for not only controlling the punch carrier 15 from the mandrel carrier 11 during part of its movement, but I also provide means for controlling it from another point by means of a secondary driving means. With the same secondary drive, I control the movement of a billet container 23.

The billet container 23 is supported upon a matrix die carrier 25, the latter being mounted for longitudinal movement in said frame 1 beneath and in substantially the same axis as the punch carrier 15. The container 23 has an opening 27 therein for accommodating a heated billet 29, at the lower end of which opening is located a matrix die 31, said matrix die 31 also being supported on the matrix carrier 25. The matrix die 31 has an outlet 33 which is somewhat larger in bore than the diameter of the mandrel 13, the thickness of the extruded pipe being determined by the difference in

these dimensions. An opening 35 in the carrier 25 accommodates exit of the extruded tubing (see Fig. 5) as does also an opening 37 in the bed 39 of the frame 1.

The secondary driving means, referred to above, includes a cam mechanism and a toggle mechanism in series.

The toggle mechanism comprises pivoted pairs of toggle links 41, 43 pivoted to the matrix carrier as indicated at numeral 45 and pivoted to the bed 39 as indicated at numeral 47. The lower links 43 are shaped as bell cranks having arms 49 at the ends of which are links 51 which extend upwardly and join a connecting rod 53 at a joint 55. The connecting rod 53 is vertically slidable in an outside bearing 57 and carries at its upper end a cap 59. This cap has a suitable opening 61 permitting reciprocation over an extension 63 of the crank shaft 3.

Said extension 63 of the crank shaft 3 carries a cam 65 which bears upon oppositely disposed roll followers 67 rotatably fastened by pins 69 to the cap 59. There is thus effected a positive-motion cam mechanism driven from the same source as the main drive for the purpose of reciprocating the connecting rod 53, said rod 53 in turn controlling the described toggle linkage so that it moves from the position of Fig. 3 to the position of Fig. 4. This movement occurs once per revolution of the crank, because the cam 65 is of the single lobe type.

The cam has a rising portion 71 subtending an angle of 60° for driving down the rod 53, a raised constant radius portion 73 subtending an angle of 120° for holding down the connecting rod 53 and providing the position of the toggle linkage shown in Fig. 4, a descending portion 75 subtending an angle of 60°, and a lower, constant radius portion 77 subtending an angle of 120°. Inasmuch as the cam mechanism is of the positive-motion type, the connecting rod 53 is positively reciprocated, independently of gravity, and thus the toggle links 41, 43 may be definitely dead centered, as shown in Fig. 4, and still be readily re-opened. The limiting stops 79 which are effective at dead center of the toggles cause the toggles to function as columns and result in taking the strain of the extruding operation off the cam mechanism, as will be seen later. This is of advantage, because a cam mechanism should, if possible, be relieved of excessive forces.

The operation of this form of the press is as follows:

In the initial position, shown in Figs. 1 to 3, the heated metal billet 29 is inserted into the opening 27. The cam is then in the position shown in said Figs. 1 to 3 and the follower cap 59 is in its uppermost position and about to descend.

The press is then set to work, the crank shaft 3 being driven from said suitable outside source. As the crank 3 and the cam 65 are turned through an angle of substantially 60° (clockwise, Fig. 2; counterclockwise, Fig. 3), the mandrel carrier 11 makes only a small part of its downward movement, whereas the billet container 23 and the matrix die 31 are forced upwardly through 10 a complete stroke, whereby the piercing of the billet 29 is effected primarily by the upward movement of the matrix carrier 25 and to a lesser degree by the downward movement of the mandrel 13 (Fig. 4).

15 It will be seen that during the upward stroke of the matrix carrier 25 from the Fig. 3 position to the Fig. 4 position, the punch 19 has been engaged by the billet 29 in the container 23, thus stripping the punch 19 back from the mandrel 13, said mandrel at this time entering the billet 29. The stripping action of the punch 19 from the mandrel 13 is permitted by the provision for 20 said relative movement between the punch carrier 15 and the mandrel carrier 11. Immediately prior to the event of Fig. 4, the swelling action of the billet, caused by piercing, aids in and/or effects raising of the carrier 15.

25 It will be noted that the angularly located toggles 41, 43 are in a position of low mechanical effect as the upward stroke of the container 23 is started (Fig. 3), but as a result of this, the upward movement is exceedingly rapid. This is desirable, because time is gained during the low-load period when no piercing or extrusion takes place. Then as the toggles straighten out 30 into their positions of highest mechanical effect (Fig. 4), the speed of the raising action on the carrier 25 decreases and the actual work of piercing is done at a better mechanical effect. By means of the initial quick action of the toggles, I am enabled 35 to prevent excessive cooling of the hot billet and extrude it under optimum conditions of heat.

The position of the cam when the toggles are straightened may be seen in Fig. 4, this 40 figure also showing the cap 59 in lowermost position and the carrier 25 with its matrix die 31 supported on the toggle columns for sustaining the on coming force due to extrusion, without transmitting that force 45 back to the cam mechanism.

Upon further movement of the crank from the 60° position referred to above, the mandrel carrier 11 continues its descent, accelerating according to the law of simple 50 harmonic motion, modified according to the ratio between the length of the rod 7 and throw of the crank 5. The carrier 11 proceeds from the Fig. 4 position to drive the punch carrier 15 downwardly (which at 55 this time is supported by the punch 19 on

the hot billet 29), so that the punch extrudes the billet through the opening 33 and around the mandrel 13 as a tube. During this portion of the stroke, because of the constant diameter of the cam 65, the fixed position of the matrix die 31 is not altered. 70 It is held rigidly in place with the toggle columns 41, 43 (see Figs. 4 and 5). The extruding action is accomplished over the most advantageous conditions of speed, acceleration and deceleration which are offered by the simple slider-crank mechanism. 75

After the extruded tube 81 has been formed (Fig. 5), the cam raises its follower, thus drawing down the matrix carrier 25 by means of the toggle linkage 41, 43. At the same time the slider-crank mechanism draws up the mandrel carrier 11 in the punch carrier 15 until said mandrel carrier 11 touches the abutment 17 after which said punch carrier is raised. Thus during the back stroke, the parts are 80 returned to their initial positions by the motion of the crank and of the cam. The tube 81 and pressing residue 83 are then 85 removed in the known manner.

It will be understood that if it is desired to extrude a rod, it is only necessary to remove the mandrel, or at least its effective 90 part, and proceed as before.

I am aware that full-stroke, crank presses have been used, but it is not desirable to use the full stroke, because the delay in the initiating of the flowing process and the low 100 extruding speed at the beginning of the extrusion process (both connected with the use of the full stroke) causes serious drawbacks which detract from the advantages gained.

The law of motion of a crank press is such that at the beginning of the movement of the crank the motion of the punch sets in very slowly. Further there are retardations in the initiating of the flowing of the metal, because the whole frame of the press must 105 be first brought up to the full working tension, and because the billet does not completely fill up the container, even after the billet is pressed upon and is pierced. Furthermore, that portion of the billet which forms the first extruded part of the tube, that is, the edge of the tube formed by the 110 surface of the billet which faces the matrix die, comprises a critical cooling zone; and any retardation in operation at the start 115 of the stroke will manifest itself in increased cooling, which is detrimental. This cooling will have more disadvantageous effects, the higher is the temperature at which the billet 120 is to be worked. The present invention extrudes the first and other parts of the tube with the least possible delay.

125 Further advantages are that the punch carrier which is arranged to slide toward the mandrel carrier permits of the punch 130

pressing on the billet within the container prior to piercing. Then during the piercing operation the mandrel is guided by the punch and the billet is maintained under pressure by the weight of the punch and the punch carrier. Furthermore, during the extruding operation, the mandrel moves with the punch carrier so that the relative motion between the extruded metal and the mandrel is reduced.

In Figs. 6 to 9 is shown a modified form of the invention comprising what may be termed a kinematic inversion, because the slider-crank mechanism operates the matrix carrier and the cam mechanism operates the punch and mandrel carriers.

In this form, numeral 85 represents the frame of the machine. The crank shaft 87 carries side cranks 89 near its ends and is coupled with the matrix carrier 91 by means of connecting rods 93. The matrix carrier 91 slides in the frame 85. Numeral 23 indicates the billet container, as in the first-described form, and numerals 29 and 31, the billet and matrix die respectively.

The cam 65 is keyed centrally to the crank shaft within the frame 85 and operates upon followers 67 arranged in a cap 59. It will be noted that this arrangement is similar to the one described in connection with the other form of the invention, a difference being that it is located centrally on the shaft. The cap 59 is provided with a suitable opening 95 for accommodating motion around the crank shaft 87.

The cap 59 directly drives the mandrel carrier 97 which is slidable in the frame 85. Suspended from the mandrel carrier 97 is the punch carrier 99 which carries the punch 19. As in the other form, the mandrel 13 extends downwardly from the mandrel carrier 97 and passes through the punch 19. The bolts 101 which support the punch carrier 99 are threaded in said punch carrier 99 and pass slidably through the mandrel carrier 97, the heads 103 of said bolts 101 forming limiting stops to limit the relative movement between the punch and mandrel carriers 99, 97.

The operation of the alternative form is as follows:

After inserting the heated billet 29, the cam is in the position shown in Figs. 6 and 7, the cranks extending downwardly. During the first phase of the stroke, proceeding from the Fig. 7 to the Fig. 8 position, the cam 65 causes the punch and mandrel carriers to quickly descend. The matrix carrier, together with the container and billet, is moved upwardly by the crank mechanism, but this movement starts out more or less slowly, so that most of the absolute movement is provided by the cam mechanism. During this first phase the punch 19 is set down on the billet 29 to function as

a closure and as a guide for the mandrel 13; and the mandrel carrier 97 is driven down to the punch carrier 99 so that the mandrel 13 effects its piercing operation (see Fig. 8).

It will be appreciated that during the piercing movement of the mandrel 13 there is an accelerated upwardly movement of the matrix carrier with its container and billet. During this operation the punch carrier for a short period of time stands still, because there is some compression which takes place as its weight is applied to the billet 29. The rising metal caused by displacement due to piercing effects a backward movement of the punch carrier 99 just prior to its touching the mandrel carrier.

Upon the third phase of the stroke (Fig. 9) the mandrel carrier 97 and punch carrier 99 remains stationary while the matrix carrier 91 continues its upward movement so as to cause the metal billet to exude as a tube through the annular opening between the mandrel 13 and the matrix die 31.

Upon the back stroke, the mandrel carrier, punch carrier and container return to their initial positions shown in Fig. 7.

One of the advantages of the alternative form of the invention is that the added parts comprising the toggle links are eliminated. In this form, however, the thrust of the extruding pressure is exerted upon the cam mechanism.

It will be seen that the invention above described includes two members adapted to reciprocate in substantially the same lifting axis and to be moved in directions opposite to each other, one of said members carrying a male die, referred to hereinbefore as the punch 19, and the other a female die, hereinbefore referred to as the matrix die 31 and the container 23.

The term "mechanical extrusion press" is used herein to differentiate from hydraulic and similar fluid-operated presses.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A mechanical extrusion press comprising two members mounted for opposed movement, an extruding die on one of said members and means cooperating with said die to extrude therefrom located on the other of said members and mechanical driving means adapted to move said members simultaneously at different speeds.

2. An extrusion press comprising two members adapted to reciprocate in substantially the same axis and to be moved in directions opposite to each other alternately to bring said members into and out of contact, a male die secured on one of said members, a female die mounted on the other member, and mechanical driving means adapted to operate said members simultaneously but with different speeds, and to stop one of said members during the extruding stroke.
3. An extrusion press comprising two members adapted to reciprocate in substantially the same axis and to be moved in directions opposite to each other, a male die secured on one of said members, a female die mounted on the other member, a primary mechanical means for moving one of said members throughout the whole stroke, and a secondary means adapted to move the other member substantially but with a speed different from that effected by the primary means and during only a part of the stroke.
4. An extrusion press comprising two members adapted to reciprocate in substantially the same axis and to be moved in directions opposite to each other, a male die secured on one of said members, a female die mounted on the other member, a primary mechanical means for operating one of said members throughout the whole stroke, and a secondary means adapted to operate the other member simultaneously but with a speed different from that effected by the primary means and during only a part of the stroke, said secondary means deriving movement and being controlled from the driving element of the primary driving means.
5. An extrusion press comprising a reciprocating member, a crank mechanism for operating said member throughout a complete stroke, a tool arranged on said member, a cam mechanism driven from said crank mechanism, a slideable carrier, a die on said slideable carrier and means for transmitting the movement of said cam mechanism to said die carrier to move the latter in a direction opposite to the movement of said reciprocating member.
6. In an extrusion press, a toggle linkage, a reciprocating member, a crank mechanism for operating said member throughout the whole stroke, a male die arranged on said member, a cam secured on the crank shaft of said crank mechanism, a follower for said cam, a female die carrier adapted to be slid in substantially the same axis as the first named reciprocating member but in a direction opposite to that of said first reciprocating member, a rod having one end which is secured to said follower and the other end of which is coupled to the toggle linkage, said toggle linkage being adapted to be straightened by the downward movement of said follower, thereby bringing the female die into an extruding position.
7. In an extrusion press, a reciprocating member, a crank mechanism for moving said member throughout a whole stroke, a punch and a mandrel secured on said reciprocating member, a cam secured on the crank shaft of said crank mechanism, a follower acted upon by said cam, a female die carrier adapted to be slid in substantially the same axis as the first-named reciprocating member but in a direction opposite to that of said first reciprocating member, and means for transmitting the movement of said follower to said female die carrier to bring the latter into a piercing and extruding position.
8. In an extrusion press, a reciprocating member, a crank mechanism for moving said member throughout a whole stroke, a hollow punch, a piercing mandrel secured on said member and guided in said hollow punch, a secondary reciprocating member mounted slidably with respect to the first-named reciprocating member and guided in the press frame, said secondary member being adapted to be slid in substantially the same axis as the first-named member, said punch being secured on said secondary reciprocating member, means to hold both reciprocating members in their most remote relative position to each other during a part of the stroke to effect a pressure on the billet by the punch when the latter touches on the billet and to permit the punch to be pushed back by the rising material while the billet is being pierced, a cam secured on the crank shaft, a follower acted upon by said cam, a female die carrier adapted to be slid in substantially the same axis as the first-named reciprocating member but in a direction opposite to that of said first reciprocating member and means for transmitting the movement of said follower to said female die carrier to bring the latter into a piercing and extruding position.
9. In an extrusion press, a reciprocating member, a billet container, a female die, said container and die being mounted on said reciprocating member, a crank shaft, a crank mechanism for operating said reciprocating member throughout a whole stroke, a second reciprocating member adapted to be slid in substantially the same axis as the first-named reciprocating member but in a direction opposite to that of said first reciprocating member, a male die secured on said second reciprocating member, a cam mounted on the crank shaft, a follower for said cam and means connecting said follower and second reciprocating member whereby the male die is brought into an extruding position.
10. In an extrusion press, a reciprocating member, a billet container and a female die

- both mounted on said reciprocating member, a crank mechanism for operating said reciprocating member throughout a whole stroke, a compound reciprocating member adapted to be slid in the same axis as the first-named reciprocating member but in a direction opposite to that of said first reciprocating member, a punch and a mandrel secured on said compound reciprocating member, a cam mounted in operation connection with the above crank mechanism, a follower for the cam, and means connecting said follower and compound reciprocating member whereby the male die is brought into the extruding and piercing position. 15
11. In an extrusion press, a frame, a crank shaft, a reciprocating member, a billet container and a female die both mounted on said reciprocating member, a crank mechanism for operating said reciprocating member throughout a whole stroke, a second reciprocating member adapted to be slid in the same axis as the first-named reciprocating member but in a direction opposite to that of said first reciprocating member, a piercing mandrel secured on said second reciprocating member, a hollow punch, said mandrel being guided in said hollow punch, a third reciprocating member mounted to slide with respect to said second reciprocating member, and slidable in said frame, said punch being secured on said third reciprocating member, said third member being adapted to be slid within certain limits in substantially the same axis as said second member towards and away therefrom, means to hold both reciprocating members in their most remote relative position during a part of the stroke to effect a pressure on a billet by the punch when the latter touches on the billet and to permit the punch to be pushed back by the rising material while the billet is being pierced, a cam mounted on the crank shaft and a follower for the cam for bringing the male die into an extruding position. 30 35 40 45 100 105 110
12. An extrusion press comprising two members mounted for opposed movement, a male die secured on one of said members, a female die mounted on the other member, and mechanical driving means adapted to move said members simultaneously. 50 115
13. An extrusion press comprising two members mounted for opposed movement, a die secured on one of said members, another die mounted on the other member, and mechanical driving means adapted to move said members simultaneously at different speeds. 55 120
14. An extrusion press comprising a reciprocable billet container and die, a reciprocable mandrel, a punch reciprocable with respect to said mandrel and die, means for reciprocating the die, means for reciprocating the mandrel and punch, and a toggle linkage for moving the die adapted to prevent transmission of load on the die back to the means for reciprocating the die when said die is in an extreme position. 60 65 70 75 80 85 90 95 100 105 110 115 120 125 130
15. An extrusion press comprising a reciprocating die, a reciprocating forming tool cooperating with the die, means for reciprocating the die, means for reciprocating the forming tool, the movements of the die and forming tool being opposed to perform an operation and means associated with the reciprocating means for the die adapted to prevent transmission to the die reciprocating means of the load imposed upon the die by the cooperation therewith of the forming tool. 16. An extrusion press comprising a reciprocable billet container and die, a reciprocable mandrel, a punch reciprocable with respect to said mandrel and die, means for reciprocating the die, means for reciprocating the mandrel and punch, and a toggle linkage for moving the die adapted to prevent transmission of load on the die back to the means for reciprocating the die when said die is in an extreme position, the motion of said punch being part of the time the same as said die. 100 105 110 115 120 125 130
- In testimony whereof, I have signed my name to this specification this 9th day of August, 1930.
- FRITZ SINGER.
